UNITED STATES PATENT OFFICE.

GLENN B. WARREN AND HARRISON L. WIRT, OF SCHENECTADY, NEW YORK, AS
SIGNORS TO GENERAL ELECTRIC COMPANY, A CORPORATION OF NEW YORK.

ELASTIC-FLUID TURBINE.

Application filed July 12, 1922. Serial No. 574,386.

To all whom it may concern:

Be it known that we, GLENN B. WARREN and HARRISON LORING WIRT, citizens of the United States, residing in Schenectady, 5 in the county of Schenectady, State of New York, have invented certain new and useful Improvements in Elastic-Fluid Turbines, of which the following is a specification.

The present invention relates to elastic 10 fluid turbines of the impulse type and particularly to nozzles for such turbines. As is well understood, the nozzles are stationary, fluid-directing elements which serve to expand the elastic fluid, thereby converting 15 pressure into velocity, and direct it against the adjacent bucket ring of the rotating wheel. In general, the nozzles are formed by mounting or arranging guide blades or partitions between two radially spaced 20 concentric rings, the structure as a whole being termed a nozzle diaphragm. The nozzles may extend entirely around the diaphragm providing for complete peripheral admission or they may extend only part way around.

25 In multi-stage turbines of considerable size, the length of the buckets of successive stages increases quite rapidly especially in the last stages and this requires that elastic fluid leaving one ring of buckets must be 30 expanded radially before being directed to the next ring of buckets in order that the elastic fluid may strike the next ring of buckets throughout their lengths. In other words, it requires that the nozzle passages 35 increase in radial depth from their entrance edges to their exit edges in order to convey the elastic fluid from the shorter ring of buckets to the next longer ring of buckets. Such nozzles are ordinarily termed flared 40 nozzles and are well known in connection with turbines of this general type. With such nozzles, it has been found that the elastic fluid in flowing through them does not discharge in a perfectly axial direction but 45 that it discharges at an angle to the axial so that instead of striking the buckets at a right angle, a thing which is desirable in order to obtain the highest efficiency, it strikes the buckets at an angle other than a right angle. 50 In other words, the elastic fluid issuing from the nozzles has a considerable component in a radial direction.

The object of our invention is to provide an improved nozzle structure or nozzle diaphragm structure wherein with nozzles of

the flaring type the elastic fluid will be discharged in a truly axial direction, and for a consideration of what we believe to be novel and our invention, attention is directed to the accompanying description and the 60 claims appended thereto.

In the drawing, Fig. 1 is a side elevation of a portion of a nozzle diaphragm embodying our invention, the view being taken looking toward the discharge side of the diaphragm; and Fig. 2 is a sectional view taken on an irregular section between two of the nozzle partitions.

Referring to the drawing, 5 indicates a nozzle diaphragm having nozzle partitions 6. The entrance edges of the nozzle partitions are designated 7 and the discharge edges 8. The bucket wheels of the stages preceding and following diaphragm 5 are indicated at 9 and 10, and as will be noted 70 the buckets of wheel 10 are substantially longer than those of wheel 9, which require that the nozzle passages increase in radial depth from their admission to their exit edges, as shown particularly in Fig. 2, in order to direct elastic fluid to the buckets of wheel 10 along their entire length. The foregoing may be taken as typical of a diaphragm between two successive stages and the wheel structures of such stages. As is 80 well understood, in the arrangement illustrated, the wheels are in the form of discs fixed to the turbine shaft and carrying the bucket rings on their peripheries, and the diaphragm comprises a web portion having 85 an opening through which the shaft passes and a ring surrounding the web portion between which and the web portion the nozzle partitions are arranged. In general, nozzle diaphragms are formed in upper and 90 lower halves to facilitate assembling.

As already stated, elastic fluid in flowing through flared nozzle passages acquires a component in a radial direction and according to our invention we so shape or form the 100 nozzles that there will be produced by them a second radial component which is opposed to that due to the flared nozzle and which will neutralize or substantially neutralize it, whereby the resultant will be a discharge of 105 elastic fluid from the nozzles substantially perpendicular to the buckets. We have found that elastic fluid in passing through a nozzle tends to discharge at a right angle to the throat or narrowest cross sectional area 110

of the nozzle and according to our invention we so shape the nozzle that the plane of such throat or cross sectional area instead of being radial extends at an angle 5 to the radial, the plane of the throat making such an angle with the radial that it tends to produce a radial component in the elastic fluid flow of such magnitude and direction as to neutralize or substantially neutralize 10 the radial component in the elastic fluid flow which the flaring of the nozzle tends to create. The result is that the elastic fluid issuing from the nozzles is given a direction so it strikes the buckets at a right angle.

15 Referring now particularly to the drawing, we have illustrated a nozzle structure in which the throat or narrowest cross section occurs at the exit edge of the nozzle, and the desired angle with the radial is 20 given to the throat by making the exit edges 8 of the nozzle partitions extend at an angle to the radial. This is particularly shown in Fig. 1 where the dotted line *a* is radial and the angle *b* represents the angle 25 which the throat makes with the radial. Viewed from one aspect it may be considered that the nozzle partitions have been tilted forward from the radial several degrees as represented by the angle *b*. The 30 angle which the plane of the throats must make with the radial in order to produce a correcting component of the desired amount depends upon the amount which the nozzles flare and is a thing which can be determined for any particular case by experiment and calculation.

In the arrangement illustrated in the drawing the flare of the nozzles is radially outward so they tend to produce a component 40 in the elastic fluid flow away from the center of the diaphragm. Accordingly, the throat of the nozzle is tilted in a direction toward the center of the diaphragm so as to produce a component in the elastic fluid 45 flow toward the center.

In accordance with the provisions of the patent statutes, we have described the principle of operation of our invention together with the structure and arrangement which 50 we now consider to represent the best embodiment thereof, but we desire to have it understood that the structure and arrangement shown is only illustrative and that the invention may be carried out by such other 55 means as come within the scope of the appended claims.

What we claim as new and desire to secure by Letters Patent of the United States, is:—

1. A diaphragm for elastic fluid turbines 60 in which the nozzle passages flare in a radial direction, characterized by the fact that the nozzle partitions are so shaped that the plane of the throat of each nozzle is at an angle to the radial and serves to impart to 65 elastic fluid flowing through the nozzle a radial component opposed to the radial component which the flared nozzle passage tends to create.

2. A diaphragm for elastic fluid turbines 70 in which the nozzle passages flare in a radial direction, characterized by the fact that the nozzle partitions are so shaped that the throats of the nozzles stand at such an angle to the radial that they tend to give to 75 the elastic fluid flowing through them a radial component opposed to that which the flared nozzle passage tends to create.

3. A diaphragm for elastic fluid turbines 80 in which the nozzle passages flare radially outward characterized by the fact that the nozzle throats stand at such an angle to the radial that they tend to discharge elastic fluid in a direction having a component toward the center of the diaphragm.

4. A nozzle diaphragm having radially flared passages, and nozzle partitions having discharge edges which stand at an angle 90 to the radial to provide nozzle throats which tend to discharge elastic fluid at an angle to the axial opposed to the angle to the axial at which the flared passage tends to discharge elastic fluid.

5. A nozzle diaphragm having radially outwardly flared passages and nozzle partitions which provide discharge throats inclined toward the center of the diaphragm.

6. A nozzle diaphragm having radially outwardly flared passages and nozzle partitions having their discharge edges inclined toward the center of the diaphragm.

7. A nozzle diaphragm having radially outwardly flared nozzle passages the throats of which occur at the discharge edges of the nozzle partitions, said discharge edges being inclined toward the center of the diaphragm.

In witness whereof, we have hereunto set our hands this 11th day of July, 1922.

GLENN B. WARREN.
HARRISON L. WIRT.
